UNITED STATES PATENT OFFICE.

REYNOLD JANNEY, OF NEW YORK, N. Y., ASSIGNOR TO THE WATERBURY TOOL COMPANY, OF NEW BRITAIN, CONNECTICUT, A CORPORATION OF CONNECTICUT.

GEARING.

1,071,619.

Specification of Letters Patent. Patented Aug. 26, 1913.

Application filed September 19, 1912. Serial No. 721,194.

To all whom it may concern:

Be it known that I, REYNOLD JANNEY, a citizen of the United States, residing at New York, in the county of New York and State of New York, have invented certain new and useful Improvements in Gearing, of which the following is a specification.

This invention relates to gearing one of the primary purposes of the invention being 10 to provide means of this character whereby one member may drive another directly or through an independently-controlled drive-modifying device. Preferably but not necessarily, the drive-modifying device is 15 of such nature that changes in speed and direction of movement can be secured. Gearing involving my invention can be employed with advantage in many different connections.

20 There are many instances wherein a perfect control both as to speed and direction of movement are of the highest importance whereas the power efficiency is not of so great consequence while at other times the 25 transmission of power of as high efficiency as possible, is essential, the control of speed and direction of movement being not so important, as one illustration of the many. submarine craft may be mentioned. While 30 maneuvering these vessels in a harbor it is of the utmost importance that the operator be able to control his power very completely and perfectly, not only in speed but in direction of movement, the transmission 35 of power of the highest efficiency not being of such great consequence at such time. The same may be said at the time of immediate attack on an enemy's ship; indeed at this moment the success of the attack depends 40 upon the perfect control of the vessel's movement. When such a vessel is making a long run from port to port, speed and efficiency are the important considerations. In such a case it is desirable to be able to 45 cut out any drive-modifying device and transmit the power directly. With my organization I can secure the advantages and perfect control, to which allusion has been made. As already intimated the drive- 50 modifying device is of such a nature that both changes in speed and direction of movement can be accomplished, but there may be cases where the said device would have means merely to effect changes in speed 55 without changing the direction of movement

and vice versa although in the case of a submarine craft, both conditions are required.

Another important feature of the invention is the provision of means whereby the 60 action of the control or equivalent members, except in a definite or predetermined order, is positively and effectually prevented.

There are other features of novelty and advantage which with the foregoing will be 65 set forth at length in the following description wherein I will describe in detail that one of the several forms of embodiment of the apparatus, which I have selected for convenience of illustration, in the drawings accompanying and forming part of the present specification. It will be clear that I do not restrict myself to such disclosure; I may depart therefrom radically in several respects within the scope of the invention 70 defined by the claims following said description.

Referring to said drawings:—Figure 1 is a top plan view of gearing embodying my invention. Fig. 2 is an elevation of said 80 gearing. Fig. 3 is an end view of the same as seen from the right in Figs. 1 and 2. Fig. 4 is a longitudinal section on the line 4—4 of Fig. 1. Fig. 5 is a transverse section on the line 5—5 of Fig. 4. Fig. 6 is a 85 top sectional view of a portion of the right end of Fig. 4. Fig. 7 is a cross section on the line 7—7 of Fig. 6. Figs. 8, 9, 10 and 11 are diagrammatic top plan views hereinafter more particularly described. 90

Like characters refer to like parts throughout the several views which it will be observed are on different scales.

The apparatus involves in its make-up a driving member which may be of any suitable kind; the shaft 2 answers satisfactorily in this connection, being preferably in practice driven by power such as that derived from an electric or gasoline motor 2' (shown conventionally in Figs. 8 to 11) or in any 95 other desirable way. As shown said shaft is coupled by the coupling member 3 to the engine or motor shaft 4. There is also a driven member which also may be of any convenient nature, the shaft 5 being shown 100 for such purpose. The driving and driven shafts 2 and 5 are adapted to be put into or out of driving relation, preferably but not necessarily at will, and while any suitable means may be utilized for this purpose 105 110

clutch means can be very well utilized, as will hereinafter appear. In conjunction with the driving and driven members such as the two shafts, there is a drive-modifying device which may be of any desirable kind. As already stated the drive-modifying device may be of such nature as to effect changes in direction of movement or speed or both but I prefer that it be of the latter nature in that the same is highly advantageous in many different ways, allusion having been specifically made to one. What is known as a "hydraulic variable speed gear" answers my requirements, the same having as a part thereof, means for controlling it, independently of the driving member or shaft 2. The hydraulic variable speed illustrated in the drawings is denoted in a general way by 6, and as it is well-known in the art, it requires no detailed description. As will hereinafter appear said hydraulic variable speed gear, is adapted for operative connection with both the driving and driven shafts, and while any suitable means may be provided for putting said hydraulic variable speed gear into and out of working relation with said shafts, clutch means is quite satisfactory as will hereinafter appear. In the case of a submarine craft or in fact any other connection, where the maximum power efficiency is required the driving shaft 2 will be put into direct driving connection with the driven shaft 5, whereas when precision of control is a necessity, as in maneuvering such a ship, both said shafts will be put into operative relation with the hydraulic variable speed gear 6 so that through the independent control of the latter, as will hereinafter appear, the driven shaft 5 can be also governed both as to speed and direction of movement, it being understood that when the apparatus is installed on a ship, the propeller thereof is connected with the driven shaft 5.

In the construction shown the two shafts 2 and 5 are co-axial although this is not essential, their inner ends being adjacent. The base or bed 7 which carries the different parts, is represented as provided with up-standing bearings 8 which sustain the two shafts. The driving or power operable shaft 2 is shown provided with a clutch-member 9 fastened, as by pinning, thereto, said clutch member being practically at the inner terminal of said shaft. The companion shaft 5 is shown equipped with a clutch member 10 slidably-keyed thereto, and preferably manually-operable. It will be understood that when the two members 9 and 10 are out of engagement, the shaft 2 will not directly drive the complementary shaft 5, but that if said two clutch members are engaged such a drive will follow, provided that the shaft 2 is in motion.

The hydraulic variable speed gear device

6 comprises the ingoing shaft 11 and the outgoing shaft 12, and its casing as well known, incloses mechanism, by which the speed and direction of movement of the outgoing shaft can be governed by a control member externally accessible and usually manually-operable as will hereinafter appear. The ingoing shaft 11 is shown having fastened thereto, the spur-gear 13 in mesh with the pinion 14 loose on the driving shaft 2, said pinion having an elongated hub 15 supported in the head of the bearing or upright 8 at the left in Figs. 1 and 2. Said hub 15 terminates at its inner end, in the clutch member 16 which it will be evident is loose on said shaft 2. Slidably-keyed to said shaft 2 between the fixed and loose clutch members 9 and 16, is the clutch member 17. Fastened to the outgoing shaft 12, is the spur gear 18 in mesh with the pinion 19, the elongated hub 20 of which is supported in the head of the bearing 8 at the right in Figs. 1 and 2, being provided with a rigid clutch member 21, which with the pinion 19 and hub 20, are loose on the shaft 5, said clutch member 21 being co-operative with the clutch-member 10 already described. The clutch members 10 and 17 are shown as occupying their neutral positions in Fig. 8 so that if the shaft 2 is in motion, the shaft 5 will not be driven either directly or indirectly. If the clutch member 17, however, be engaged with the clutch member 16, thus connecting the pinion 14 to the shaft 2, and if the clutch member 10 be engaged with the clutch member 21, thus connecting the pinion 19 with the shaft 5, both shafts 2 and 5 will be put into operative relation with the hydraulic variable speed gear 6 as shown in Fig. 9 by reason of which the shaft 5 will be driven through said device 6 and be controlled by the control of the latter, so that the shaft 5 may be driven either fast or slow or in opposite directions through the primary agency of the shaft 2 acting through the intermediate device 6.

In Fig. 11, the clutch member 10 is shown in working engagement with the clutch member 9 and out of operative relation with the clutch member 21 while the clutch member 17 is shown as being out of engagement with the clutch member 16 by reason of which the two shafts 2 and 5 are directly clutched to each other, the hydraulic variable speed gear 6 at this time being out of operative relation with both shafts; this as will be evident is the direct driving relation where high power efficiency is the desideratum.

While the mechanism thus far described is advantageous I can as will be obvious employ means specifically different from those described for securing the ends in view, the invention residing rather in certain broad relations rather than in any particular

mechanism, probably the broadest feature of the invention being the combination of a driving member and a driven member, means whereby they can be operatively connected, an independently-controlled drive-modifying device, and means whereby the latter can be put into working relation with both said members. As will hereinafter appear interlocking means is preferably provided and is of such character that the action of certain members in any other than a definite order, is effectually and positively prevented.

As is well known, a hydraulic variable speed gear, includes a controlling member which ordinarily has a neutral position and in certain existing types of such a device, this part is known as a "tilting box." When the tilting box is in said neutral position, the outgoing shaft as 12 will be at rest while when said tilting box is moved in one direction from said neutral position, said outgoing shaft is operated, said outgoing shaft progressively increasing in speed as the tilting box is moved farther from said neutral position. When the tilting box is moved oppositely from said neutral position the outgoing shaft is reversed and its speed progressively increased as said tilting box is moved farther from said neutral position all as is quite common. This tilting box may be considered as a primary control member, the secondary control member being directly operable by the operator and consisting as shown, of the hand-wheel 25 fastened to the shaft 26 keyed to which is the pinion 27, the purpose of which will be hereinafter explained. Said shaft 26 in practice is connected with the tilting box to which I have already referred and it and the wheel carried thereby are well known in the art. As understood the turning of this wheel governs the outgoing shaft 12 of the hydraulic variable speed gear. If the wheel be turned in one direction said shaft 12 will be rotated in a forward direction while opposite turning of the wheel results in reversing said outgoing shaft. Manipulating this wheel therefore effects predetermined movements or stops the driven shaft 5 when the device 6 is operatively connected with said shaft 5 and the driving shaft 2 which relation is shown in Fig. 9.

To shift the clutch member 10, the hand lever 30 is shown, a substantially similar lever 31 being illustrated for shifting the clutch member 17, the bracket 32 being provided to support said two levers, being bolted or otherwise suitably fastened to the casing of the hydraulic variable speed gear 6. Each of the hand levers 30 and 31 is provided with a spring-actuated latch pin 33 operable by a spoon 34 thereon after the usual fashion and adapted to engage in stop holes in the web 35 constituting part of the

bracket 32, to thereby yieldingly hold said levers in their respective shifted positions.

As will hereinafter appear there are interlocking means between the primary or main control member 25 and the two clutch-operating levers 30 and 31, of such character that said parts can be operated only in a definite way by reason of which it is impossible to put the parts out of order. This interlocking means may vary radically as to character although that illustrated and now to be described is quite satisfactory.

In mesh with the pinion 27 is the spur gear 40 turning on a stud 41 attached to an extension of the bracket 41' fastened to the casing of the device 6, the two gears being so proportioned that when the control shaft 26 is turned to its extreme angle in either direction, the gear 40 will be given not more than a half turn. On the gear 40 is the pin 42 to which one end of the connecting rod 43 is pivoted, the opposite end of said rod being connected by a pivot 44 with the slidable bar 45, the upstanding web of which has a notch 46 to receive said last mentioned pivot. The bracket 41' is longitudinally grooved to receive the body of said slidable bar 45 which it will be perceived is substantially T shaped in cross section and which presents a convenient stop member, its web having in addition to the pivot-receiving notch 46, the relief or releasing notches 47 and 48. The clutch-operating lever 30 is shown provided with an angular rigid extension 49, the lever 31 having a similar extension 50, to which are respectively connected the stop-members 51 and 52 which are shown as consisting of bars pivoted to the respective extensions and guided for movement in a straight path by the guide devices 53. On the underside of the bar 51 is the stop 54 while the companion bar 52 has a stop 55. The stops are rigidly secured to the respective bars 51 and 52. The stop 54, however, has a movable element, such as the spring-operated latch 56 the spring 57 of which constantly forces the active portion of said latch outward, by virtue of which the block or stop 54 can move freely through the notch 47 or slot 48 from one side thereof but not from the opposite side, the latter being prevented by the latch 56. The two outside notches 47 and 48 are intended at proper times, for the passage of the stops or blocks 54 and 55.

The action of the interlocking or stop mechanism is as follows:—In Fig. 8 the control shaft 26 of the variable speed gear 6, stands at zero or neutral, the stop member or bar 45 being in its extreme retracted position or that farthest to the left in said view. In this relation, the block or stop 54 is in the path of the stop member 45 and the stop 55 is in the notch 48, so that the stop member 45 cannot be operated, until

the two levers 30 and 31 are moved to positions to effect the release of said stop member 45. The consequence is that if the shaft 2 is in motion which it is assumed to be, it will be the only operating part. In Fig. 9 the lever 30 has been swung to the right while the companion lever 31 has been swung to the left by reason of which the clutch member 10 will be engaged with the clutch member 21 while at the same time the clutch member 17 will be put into engagement with the clutch member 16, which results in putting the variable speed device 6 into operative relation with the two shafts 2 and 5. If the hand wheel 25 and the tilting box associated therewith be in zero or neutral position, the shaft 5 will not be operated nor will it be until said hand-wheel is moved from its neutral position. The instant, however, that said hand-wheel is operated, the stop member or bar 45 is longitudinally shifted, thus carrying the effective portion or the uncut part of its web into the path of movement of the stops 54 and 55 and locking the levers to which said stops are connected, in their shifted positions and said levers can only be released when the said stop bar 45 is returned to its original position. To drive the shaft 5 directly from the shaft 2, the lever 30 will be swung to the left to cause the clutch member 10 to engage the clutch member 9 as shown in Fig. 10, this operation being done when the stop bar 45 is in its retracted position, the lever 31 being retained in its shifted position. As soon as said lever 30 is thus shifted, the stop member 45 is advanced to its extreme position as shown in Fig. 10, so that the stop 54 cannot be moved through the notch 47; consequently before the lever 30 can be released it is necessary to return the stop member 45 to its initial position. At the same time said stop member 45 by locking the stop 54 also prevents shifting of the lever 31. Notwithstanding the fact that at this time, the variable speed gear device 6 is in action, it is not clutched to the shaft 5 so that said variable speed gear device has no effect whatsoever on said shaft 5, the pinion 19 at this time running idly on said shaft 5. To disconnect the variable speed gear device from the shaft 2, it will be necessary to return the stop bar 45 to its original position, at which time the notch 48 will be brought opposite the stop 55 while at the same time the inner end of said stop bar will be carried slightly beyond the stop 54, as shown in Fig. 11, at which point both levers 30 and 31 will be released so that the lever 31 can be swung to the right to disconnect the device 6 from the shaft 2 and wholly cut out said device 6 and cause the direct drive of the shaft 5 from the shaft 2. All that is now required to restore the parts to their normal posi-

tions as shown in Fig. 8 is to swing the lever 30 to the right in Fig. 11 to bring the clutch member 10 to its neutral position at which point as already set forth and as indicated in said Fig. 8, the shaft will be the only moving part of the apparatus. 70

By the construction described, it will be seen that I provide means for positively preventing rotation of the outgoing shaft 12 of the variable speed gear 6 when the control shaft 26 is in zero or neutral position. Said means is also preferably of such nature as to prevent the connection directly of the two shafts 2 and 5, while the variable speed gear 6 is operatively connected to them both which is of advantage in that at such time, the speed of the gears 18 and 19 might not correspond with that of the shaft 5 when driven directly. Said means is also of such nature that the ingoing shaft 11 of the variable speed gear device, cannot be connected unless the control shaft 26 be at zero as otherwise there might be a conflict of speeds between the wheel 14 and the shaft 2. Said means also prevents the clutching of the shaft 5 with the gear 18 through the gear 19 except when the control shaft 26 is at zero as otherwise the shaft 5 might be required to drive said wheels 19 and 18 and through the same and the variable speed gear 6, the wheel 9 with its shaft at an excessive or impossible speed. It is of course not necessary to employ all the safety means in one installation although as will be inferred the same is highly advantageous. It will also be clear that the connections between the drive modifying device need not be like those described. In fact as already indicated the invention contemplated certain broad features and to conform to the statute I have shown the best of the several modes of carrying the invention into effect. 100 105

While in the diagrammatic Figs. 8 to 11, I have shown the clutches as being of the "dental" type, this is only for convenience of illustration, as I prefer to employ friction clutches as shown in Figs. 1 to 3. 110

What I claim is:

1. The combination of a driving member, a driven member, a hydraulic variable speed device having a manually operable control member, mechanism comprising a plurality of manually operable shifting members, for putting the driving and driven members into direct connection with each other or for putting said hydraulic variable speed device into working relation with both the driving and driven members, and stop means connected with the respective manually operable shifting devices and with said manually operable control member, the stop means of said shifting devices serving to limit the movement of those associated with said manually operable control member and vice versa. 115 120 125 130

2. The combination of a driving member, a driven member, a variable speed device having a manually operable control member, mechanism comprising a plurality of manually operable shifting devices for putting the driving and the driven members into direct connection with each other or for putting said variable speed device into working relation with both the driving and the driven members, and stop means connected with the respective shifting devices and with said manually operable control member, the stop means of said shifting devices being adapted to limit the movement of those connected with said manually operable control member and vice versa. 30
3. The combination of a driving member, a driven member, a hydraulic variable speed device having a manually-operable control member, mechanism, comprising a pair of levers, for putting the driving and the driven members into direct connection with each other or for putting said hydraulic variable speed device into working relation with both the driving and driven members, and stop means connected with the respective levers and with said manually-operable control member, the stop means of the levers serv- 35
- ing to limit the movement of those associated with said manually-operable control member and vice versa. 40
4. The combination of a driving member, a driven member, a hydraulic variable speed device having an individual controlling member, mechanism comprising a pair of manually-operable levers for putting the driving and the driven members into direct connection with each other or for putting said hydraulic variable speed device into working relation with both the driving and the driven members, a slidable stop member connected with and movable by said controlling member, and a pair of bars connected with said levers, each bar having a stop, the slidable stop member having 45 notches for the passage of said stops when the levers are in a certain position, and one of said stops having a spring-operated latch to prevent the passage of said stop through one of said notches from one side thereof. 50

In testimony whereof I affix my signature in presence of two witnesses.

REYNOLD JANNEY.

Witnesses:
